MILLER REESE HUTCHISON, JR., OF MADISON, NEW JERSEY, ASSIGNOR, BY MESNE ASSIGNMENTS, TO ACOUSTIC PRODUCTS COMPANY, OF NEW YORK, N. Y., A CORPORATION OF DELAWARE

PLURAL-CONDUCTOR ACTUATING UNIT

Application filed July 1, 1927. Serial No. 202,834.

This invention relates to sound propagating devices of the type in which a mechanical diaphragm, actuated by an electromagnetic unit is employed for imparting vibrations to 5 a fluid medium.

In devices of this character, it is desirable to produce sound waves of maximum amplitude in response to a given applied force, and also to provide a device which is 10 capable of substantially linear sound reproduction in order to avoid distortion of the propagated waves. The mechanical arrangement for converting the electromagnetic energy into a displacement of the sounding 15 board must, therefore, be capable of operating in such manner that the displacement of the sounding board is substantially proportional to the applied current.

In accordance with the present invention, 20 the electromagnetic unit is suspended between a fixed support and a movable part of the diaphragm and is caused to execute a movement parallel to the diaphragm. This movement therefore produces an action similar 25 to that of a toggle joint, and enables a force to be exerted on the diaphragm considerably larger than that which is applied to the unit itself.

The invention further provides a coil 30 carrying a current which is placed in a magnetic field. The force tending to displace the coil from its normal position is dependent upon the strength of the field and the strength of the current passing through the coil. Consequently by applying a voice current to either the coil or to the field windings, the coil will be caused 35 to execute corresponding vibrations which are translated, by means of the toggle action above mentioned, into a displacement of the diaphragm for the propagation of sound waves.

In order to increase the force which may be exerted upon the coil by the magnetic field, a plurality of turns may be employed, 45 and the opposite sides of the coil may be inserted between pole pieces which are suitably energized for exerting a force thereon in the same direction and causing lateral displacement of the coil as a whole.

50 The invention also consists in certain new

and original features of construction and combinations of parts hereinafter set forth and claimed.

Although the novel features which are believed to be characteristic of this invention 55 will be specifically pointed out in the claim appended hereto, the invention itself, as to its objects and advantages, the mode of its operation and the manner of its organization, may be better understood by referring 60 to the following description taken in connection with the accompanying drawing forming a part thereof, in which like reference characters have been used to denote like parts in the various figures. Since such illustration is, however, primarily for purposes of disclosure, it will be understood that the structure and the method of operation 65 thereof may be modified in various respects without departing from the broad spirit and 70 scope of the invention.

One embodiment of the invention has been shown for purposes of illustration in the accompanying drawing, in which

Fig. 1 is an elevation of a sound propagating device constructed in accordance with this invention; 75

Fig. 2 is a section taken on the line 2—2 of Fig. 1; and

Fig. 3 shows diagrammatically a modification 80 thereof in which the pulsating current is applied directly to the coil.

In the following description and in the claim the various parts of the apparatus and details of the invention will be identified by 85 specific names for convenience, but they are intended to be as generic in their application as the art will permit.

Referring to the drawings more in detail, and particularly to Figs. 1 and 2, a form of 90 the invention is disclosed comprising an electromagnetic unit 10 including a pair of pole pieces 11 and a coil 12 of conducting wire comprising a plurality of turns located in the magnetic field produced by said pole pieces. 95 Windings 13 and 14 are employed for energizing the magnetic circuit and producing a magnetic field between said pole pieces. Windings 13 may be energized by a suitable source of direct current 15 and winding 14 100

may be energized by the output current of audio frequency amplifier 16 or from any other source of current the variations of which are to be converted into sound waves.

5 Pole pieces 11 are mounted upon fixed framework 20 by suitable supports 21 (Fig. 1) and coil 12 is suspended between fixed support 22 and an intermediate part of the diaphragm 23 as by connecting links 24 and 25. Said 10 connecting links may be attached to coil 12 by any suitable means as by clamps 27 which are adapted to surround said coil and are provided with clamp screws 28 for attaching the same to said connecting links.

15 Diaphragm 23 may be supported in framework 30 from base member 20, bracing 31 being provided for strengthening purposes. Coil 12 may be energized by direct current from source 32 by means of which current is 20 caused to flow serially through the various turns thereof.

Coil 12 may preferably be formed of aluminum wire which may be un-insulated since aluminum oxide is formed upon exposure 25 to the air, and provides a sufficient amount of insulation between the various turns to prevent breakdown in the ordinary range of voltages which are employed. A coil of aluminum is furthermore light and presents 30 a minimum amount of inertia, and consequently is capable of reproducing the desired vibrations without substantial distortion.

In the operation of this device a force will be exerted upon coil 12 tending to move said 35 coil in a direction parallel to diaphragm 23, said force being dependent upon the strength of the current flowing through the coil, the number of turns, and the strength of the magnetic field. Each of these elements is 40 constant with the exception of the strength of the magnetic field, which is produced by the combined effect of coils 13 and 14. Coil 14 is energized by varying current from the audio frequency amplifier and will cause the 45 magnetic field to vary directly as the current flowing therethrough, consequently the force exerted upon coil 12 will vary directly as the current flowing through coil 14 from amplifier 16.

50 The force exerted upon diaphragm 23 at right angles thereto by movement of said coil 12 is proportional to the force applied to coil 12 and the cotangent of the angle between link 25 and the normal to said diaphragm. Since the angle of movement of said coil is extremely small, this force will be substantially proportional to the force applied to coil 12. Diaphragm 23 therefore 55 will have a substantially linear characteristic and will faithfully reproduce the applied vibrations.

Since the force of said coil 12 is dependent upon the various features above enumerated, that is, the strength of the magnetic field, 60 the number of turns in the coil and the cur-

rent passing through said coil, it may be varied by varying any of the above elements. In the modification shown in Fig. 3, the voice current from amplifier 16 is shown as applied to coil 12 while the strength of the magnetic field between poles 11 is maintained constant by battery 15. The operation will be similar to that described above in connection with Fig. 1. Various other modifications might be employed, the essential feature being to produce the varying force on coil 12 and utilize this force to cause displacement of diaphragm 23.

An electromagnetic unit constructed as above is capable of operating efficiently in response to currents of small amplitudes and to exert a comparatively large force on the diaphragm or sounding board. The number of turns in coil 12 may be varied to produce the most satisfactory results. By constructing the coil of aluminum, the weight is maintained as low as possible, and a comparatively large number of turns may be employed without increasing the inertia of the device to a prohibitive value. By utilizing the inherent qualities of the aluminum whereby an oxide is formed to produce insulation between the various turns, the weight of the entire assembly is reduced since it is unnecessary to employ additional insulation.

While certain novel features of the invention have been shown and described and are pointed out in the annexed claim, it will be understood that various omissions, substitutions and changes in the forms and details of the device illustrated and in its operation may be made by those skilled in the art without departing from the spirit of the invention.

What is claimed is:

In a device of the character described, a coil, a diaphragm attached to said coil and adapted to be vibrated by movement thereof, a source of steady current for said coil, and electromagnets positioned on opposite sides of said coil, those on one side being provided with a source of steady current and those on the opposite side being provided with a source of intermittent current.

Signed at New York in the county of New York and State of New York.
